UNITED STATES PATENT OFFICE.

EDWARD W. HASLUP, OF NEW YORK, N. Y., ASSIGNEE TO ROBERT GILCHRIST, OF NEW YORK, N. Y.

PROCESS OF RECOVERING FIXED NITROGEN.

1,310,478.

Specification of Letters Patent. Patented July 22, 1919.

No Drawing.

Application filed April 8, 1918. Serial No. 227,316.

To all whom it may concern:

Be it known that I, EDWARD W. HASLUP, a citizen of the United States, residing at New York city, in the county of New York and State of New York, have invented certain new and useful Improvements in Processes of Recovering Fixed Nitrogen; and I do hereby declare the following to be a full, clear, and exact description of the invention, such as will enable others skilled in the art to which it appertains to make and use the same.

This invention relates to a process for effecting the fixation of atmospheric nitrogen as a by-product in manufacturing producer gas, and has for its object to provide a method which will be more expeditious and less costly than has heretofore been proposed.

With this and other objects in view the invention consists in the novel steps and combinations of steps constituting the process, all as will be more fully hereinafter disclosed and particularly pointed out in the claims.

In order that the precise nature of the invention may be more clearly understood it is said:—

It is well known that when free or combined alkali metal oxids or alkali earth metal oxids capable of forming salts with acids are exposed to carbon and heated to a sufficiently high temperature in an atmosphere of nitrogen free of oxidizing gases, such as oxygen, carbon dioxid, etc., that a nitrogen and carbon containing compound is formed, which at its heat of formation is volatile, or at least has the physical properties of a sublimate.

Processes utilizing this principle have been made the subjects of Patents #1,134,411; #1,134,412; and #1,134,413; each dated April 6, 1915, and issued to Samuel Peacock. But in following the procedure of said patents, it is not only essential to remove the sublimed nitrogenous compound or carbo-nitrid from a furnace chamber necessarily sealed from the air, to prevent destroying the compound, but the carbo-nitrid values must be collected and cooled out of contact with the air, by some means, and to such a temperature as will preclude their decompo-

sition upon contact with oxygen, and all in a continuous industrial operation.

The mechanical problem thus presented in carrying out an industrial procedure is evidently a very difficult one. In practice all processes of this kind for such nitrogen fixation have been limited in their operation to the use of electrically generated heat, in one form or another, for electricity seemed to furnish the only means of readily obtaining the desired temperature in a sealed furnace or oven. But electrically generated heat is comparatively costly. In fact, the heat equivalent of a kilowatt year which may cost from say \$25 to \$100 is found in less than three thousand pounds of ordinary steam coal. It is true that there are a few localities where hydro-electric power may be obtained at a cost of approximately \$15 per kilowatt year; but, it is also true that there are a greater number of locations where 3000 pounds of coal would cost from say three to four dollars only. Hence, it is obvious that a procedure which would enable the use of directly generated heat from coal in such nitrogen fixation processes would be an economic gain. Now, it is well known, in the operation of a carbon monoxid gas producer, or in the operation of a blast furnace that if one examines the furnace chamber a few feet above the air blast inlet, or tuyers, he will find the furnace gases to contain neither free oxygen, carbon dioxid, nor other readily oxidizing gases, and that the gaseous nitrogen present ranges from say 50 to 60 per cent. of the total volume. The temperature of the furnace gases at this point, also, will be found to be very high, certainly above 1000° C., while the temperature of the coke and inorganic bodies in this zone of high temperature exceeds say 1400° C. In an ordinary blast furnace, at such temperatures, most oxids in contact with carbon and in the presence of gaseous nitrogen, form a nitrogen containing compound, or carbo-nitrid, which has approximately the proportional formula RCN_2 , and which when heated with water produces ammonia. But, unless prevented, these compounds will sublime as formed, and will rise with the combustion gases to the usual furnace exit, where they will be destroyed by

contact with the air, producing a white cloud of "fume" consisting of oxids and carbonates of the combined metals present in a state of very fine sub-division. If an 5 iron blast furnace is used, the action of the carbon monoxid of the furnace gases upon the iron oxid present results in the formation of metallic iron and carbon dioxid, and this latter gas at once reacts with and de- 10 stroys the nitrogen containing sublimate, or carbo-nitrid, substantially in accordance with the following equation:—

15 If no iron oxid is present, there is still a loss of combined nitrogen, because the sublimate or carbo-nitrid, is more or less condensed by the cold charge at the furnace top, and is carried down with the descending 20 charge until it reaches a temperature high enough to combine with the silicious slag making material of the furnace charge but not high enough to cause the nitrogen compound to sublime. As a result, a silicate of the carbo-nitrid metal is formed with the evolution of free nitrogen. 25

It does not seem to have occurred to any one prior to my invention that if the furnace gases be removed from an exit located 30 so low in the furnace that no substantial condensation of said carbo-nitrids will occur, and too low for the usual reducing effect to take place, that said carbo-nitrids could be tapped out and recovered. The 35 reason why no one seems to have suggested such a procedure, probably resides in the fact that the tapping of the furnace gases in any such fashion from an iron blast furnace would render the latter inoperative; 40 and the tapping of the furnace gases in such manner from a producer gas furnace would be a useless procedure, for no carbo-nitrids would be present.

One the other hand, were not these two 45 objections present, it would be perfectly feasible to employ either a blast furnace, or a producer furnace in the manner stated, and to obtain carbo-nitrids of the character disclosed in the patents above referred to.

50 In carrying out this invention, I avoid the foregoing objections and obtain carbo-nitrids from either a blast or a producer type of furnace by proceeding as follows:—

I charge the furnace with feldspar and 55 coke, or lime and coke, or magnesia and coke, or other oxid (capable of forming a salt with an acid) and coke, precisely as an iron blast furnace, or gas producer is charged, and I make producer gas, using a 60 hot blast. In some cases, suitable fluxes may also be added to the charge, for the purpose of conveniently removing such materials as silica from the furnace as a molten slag. I prefer, however, to finely grind the 65 coke and the oxid containing salt or mineral,

and briquet the same for furnace treatment. The following four chemical equations, stated in proportional formulas, illustrate the substantial reactions that take place:—

75

75

In all four of these illustrations, the reaction involves a high temperature zone of not less than say 1400°C. If this temperature is raised to 1600°C. the alumina of the feldspar is also converted to the nitrogen 80 compound.

In carrying out the process the use of a hot blast is very desirable in most cases, in order to keep the charge sufficiently molten to secure a readily flowing slag. As no iron 85 oxids are to be reduced no objection is encountered in tapping off the furnace gases at a suitable point near the tuyers, or where the carbo-nitrids are found to be richest, and this I do. Ordinarily such a point in a 90 blast furnace is found to be at the usual reducing zone. After the furnace gases have been thus led from the reducing zone, they are carried out of contact with the air to any suitable scrubber, or collector, where 95 the carbo-nitrids contained therein are cooled down to a point where contact with the air does not affect them, and recovered without substantial loss.

It will now be clear that by making producer gas in a regular producer gas furnace, or in an iron blast type of furnace, and by having present in such furnaces a material containing an oxid of an alkali metal, or of an alkali-earth metal, during the process 105 of making said producer gas, I am enabled to not only fix atmospheric nitrogen as a by-product, without the use of electric heat, but I am enabled to continuously tap it directly 110 from the reducing zones of said furnaces and thus avoid its condensation on the cooler portions of said furnaces, and on their charge material. I am also enabled to cool 115 said carbo-nitrids without exposure to the air; results that have not been heretofore attained in so far as I am aware.

The reaction velocities are of course increased both by a hot blast and by preheating the charge, but neither is essential in all cases to the successful operation of the process. The gas which finally exits from the settlers or scrubbers is found to be a high grade producer gas suitable for use in internal combustion engines.

What I claim is:—

1. The process of producing a volatile carbo-nitrid which consists in preparing a mixture of an oxid bearing material and carbon; subjecting said mixture in a fuel fed furnace and in an atmosphere of pro- 130

125

120

125

ducer gas to a temperature sufficient to produce said carbo-nitrid; tapping out said carbo-nitrid and said producer gas from a region of said furnace too hot to permit said carbo-nitrid to condense; and separating out said carbo-nitrid from the other gases thus recovered, substantially as described.

2. The process of producing a volatile carbo-nitrid which consists in preparing a mixture of an oxid and carbon; subjecting said mixture to the action of a fuel fed furnace at a temperature and under conditions suitable for forming a mixture of producer gas and a volatile carbo-nitrid; tapping off said mixture out of contact with the air from a point in said furnace at which the temperature is sufficient to prevent the condensation of said carbo-nitrid; and recovering the latter, substantially as described.

3. The process of fixing atmospheric nitrogen which consists in preparing a mixture of carbon and a material containing an oxid capable of forming a salt with an acid; heating said mixture under conditions suitable for forming a second mixture of carbon monoxid gas and a volatile carbo-nitrid; leading off said mixture out of contact with the air before said carbo-nitrid has con-

densed; and recovering the latter, substantially as described.

4. The process of fixing atmospheric nitrogen in a fuel fed furnace which consists in charging said furnace with a mixture containing calcium oxid and carbon; heating said mixture under conditions suitable for forming producer gas and a volatile carbo-nitrid; tapping said furnace at a point the temperature of which is too high to permit the condensation of said carbo-nitrid; and cooling the latter out of contact with the air, substantially as described.

5. The process of making and recovering volatile carbo-nitrids which consists in producing said carbo-nitrids in an atmosphere of carbon monoxid gas in a fuel fed furnace; and withdrawing said carbo-nitrids before condensation along with a portion of said carbon monoxid gas, substantially as described.

In testimony whereof I affix my signature, 50
in presence of two witnesses.

EDWARD W. HASLUP.
